LIGHT DIFFUSING FIXTURE

Lawrence Ezra Cooke, 11814 Long Leaf, Houston, Tex.

Filed Nov. 23, 1960, Ser. No. 62,941

Term of patent 14 years

(Cl. D48—23)

FIG. 1 is a bottom perspective view of a light diffusing fixture showing my new design.

FIG. 2 is an end elevation thereof.

The side and end of the fixture not shown are substantially the same in appearance as the side and end shown.

The parallel lining on the sides and bottom of the fixture represents surface ornamentation.

The characteristic features of my design for a light diffusing fixture reside in the parallel lined surface ornamentation bordering the edges of the frame and extending between the lenses as shown in FIGURE 1.

What I claim is:

The ornamental design for a light diffusing fixture, substantially as shown and described.
